RETORET-CHARGING MACHINE.

1,274,120.

Specification of Letters Patent. Patented July 30, 1918.

Application filed June 7, 1917. Serial No. 173,356.

To all whom it may concern:

Be it known that we, GEORGE W. WHIPPLE and CLOISE H. BALDWIN, citizens of the United States, residing at Cherryvale, Kansas, have invented certain new and useful Improvements in Retort-Charging Machines, of which the following is a specification.

Zinc furnaces for roasting zinc ore are usually composed of a number of comparatively small retorts located within a surrounding shell of fire brick or the like in which the heating gases are circulated. The retorts are of cylindrical shape, and slightly inclined downward at the one open end, the open ends extending through one wall of the furnace. In each furnace there are usually a large number of such retorts arranged in columns of about five retorts high so as to be easily accessible. Various schemes have been designed for charging such retorts, but the usual practice is to charge them by hand, and this is a slow and laborious operation.

The present invention provides a machine by which the charging of these and similar retort furnaces can be accomplished quickly and economically.

The accompanying drawings illustrate a machine embodying the invention.

Figure 1 is a front elevation of the machine, partly in section and omitting parts of the supporting framework in order to show the novel elements more clearly;

Fig. 2 is a detail on an enlarged scale;

Fig. 3 is a transverse section (partly in elevation and also omitting parts of the supporting framework) taken approximately on the line 3-3 of Fig. 1, and showing also one column of retorts in the furnace;

Fig. 3^a is a sectional view on the line 3^a-3^a of Fig. 1;

Fig. 4 is an enlarged detail of part of Fig. 3;

Fig. 5 is a plan view, more or less diagrammatic of part of the controlling mechanism for the charging plungers of the apparatus;

Fig. 6 is a diagram of a mechanism by which the charging cylinders are brought into position against the ends of the retorts and then shifted out of such position for lateral transfer to the next column of retorts;

Fig. 7 is a diagram of a locking device for centering and holding the charging apparatus in proper relation with the column of retorts;

Fig. 8 is a diagram of a mechanism for stopping the operation of charging plungers when a retort has been filled;

Fig. 9 is a diagram of a device for "spicing" or venting the charge.

Referring to the particular embodiment of the invention illustrated, it will be understood that the furnace comprises a number of columns of retorts A (Fig. 3), each column comprising practically any desired number of retorts and the columns being arranged alongside of each other. The rear closed end of each retort rests on a shoulder provided on a rear wall B of the furnace, and the forward end of each retort rests in an opening within the front wall C of the furnace, the retorts being inclined downward as illustrated.

The charging machine is equipped with a row of charging cylinders D, one for each retort and located in the line of said retort and having a tapered head E which, when the machine is moved up against the row of retorts, enters into the open mouth of its retort so as to practically close the same. Each of these charging cylinders has an opening F at the top through which it receives a continual supply of ore by means hereinafter described. When the charging cylinders are brought into engagement with the retorts, charging plungers within the cylinders are actuated to push a portion of the ore, indicated at G, Fig. 4, into the retort. The plungers are then retracted and again advanced to push a further quantity of ore into the retorts; these operations being repeated automatically and the stroke of the plungers being shortened as the filling of ore in the retorts increases from their rear to their forward ends. The density of the charge of ore introduced determines the length of each stroke. For this reason, my apparatus secures a greater density and a greater uniformity of the charge than can be secured by hand charging methods. When a retort is completely filled the further operation of the plunger is automatically stopped. When all the retorts in a column are filled the operator shifts the machine backward a short distance to permit the ends of the charging

- 2
- cylinders to clear the front wall of the furnace, then shifts the machine sidewise to bring the charging cylinders into line with the next column of retorts and advances the 5 charging cylinders into engagement with such retorts and repeats the previous charging operations. This sequence of movements is repeated until the entire series of columns of retorts is charged.
- 10 The construction of the charging plunger is indicated in Figs. 3 and 4. It comprises an outer shell H and an inner shell J, the latter provided with a head K connected by a link to the upper end of an elliptical 15 charging disk L whose lower end is hinged just within the forward open end of the shell H. When the inner shell J is advanced with relation to the outer shell H, as it is at the beginning of and during a charging 20 movement, the charging disk L occupies the extended position shown at the bottom of Fig. 4. In retracting the plunger however, the shell J is first drawn backward to shift the disk L to the contracted position shown 25 in the upper part of Fig. 4, so that the complete plunger can be drawn back on a path clear of the ore which has been introduced into the retort, so as not to drag any of the ore out.
- 30 The movements of the charging plunger are effected by air pressure within the closed shell J, the movement of the latter being transmitted to the outer shell H through the charging disk L and connections above described. The inner shell J is therefore the 35 main plunger, the outer shell serving to cause the desired movements of the charging disk and also to protect the inner shell from distortion by heat or other causes.
- 40 The control of the air pressure is effected through a piston M which is held stationary within the reciprocating shell J, being mounted on a fixed supporting tube N on which the rear end O of the shell J is mounted with the usual stuffing box sliding on the 45 fixed tube. Within the fixed piston M is a sliding air valve P receiving air pressure from a supply tube Q. When the parts arrive at the retracted position shown in the 50 upper part of Fig. 4, the central tube Q and air valve P are shifted to the position there shown; and air from the central tube passes through the passages shown, into the forward end of the plunger, forcing the latter 55 forward. At the same time the air in the rear end of the charging plunger escapes through the outer fixed tube N as indicated by the arrows. This position of the valve continues until the forward stroke of the 60 plunger is completed.
- The valve P is then drawn back to the position shown in the lower part of Fig. 4. Here the air coming through the supply tube Q passes to the rear end of the hollow charging plunger, and the air within the forward 65
- end thereof escapes through the passages indicated to the open outer tube N; all as indicated by the arrows.
- The reciprocation of the valve and the air pressure pipe Q is effected by the mechanism indicated in Fig. 5. This pipe has a perforated portion passing through an air supply main R with freedom for slight longitudinal reciprocation. The rear end of the pipe Q is closed and is pivotally connected 70 to one arm S of a lever which is pivoted at the center and has an opposite arm T connected to a rod U which at its forward end passes through an ear V on the side of the head O of the plunger. The rod U is provided with collars W and X fastened thereon in such positions that at the end of its forward stroke the ear V which moves with the plunger will strike the tappet X, pulling the rod U forward and throwing the pressure pipe Q to the rear so as to bring the valve to the position shown in the lower part of Fig. 4 and cause a retraction of the plunger. And at the end of its rearward movement the ear V will strike the tappet W and 80 throw the pressure pipe Q forward, bringing the valve to the position shown at the top of Fig. 4 and causing the next forward movement. The controlling rod U is guided in ears on the rear side of the bearing block 85 X'; the several bearing blocks being mounted in a rear upright frame X² (Figs. 1 and 3) and the controlling mechanism being omitted from Figs. 1 and 3 for the sake of clearness.
- The control by the tappet X will continue for the first stroke or two. But when the ore becomes compacted in the rear end of the retort in substantial quantity, the stroke of the plunger must be shortened. For this 90 purpose a supplementary mechanism is provided which will shift the valve and pressure pipe Q to the position for returning the plunger as soon as the latter shall encounter an abnormal resistance to a further forward movement. When such resistance is encountered there is a momentary increase of pressure in the pipe Q and a sudden increase of pressure in a branch Y leading to a cylinder Z. In this cylinder is a piston a held 95 at the end of its stroke by a spring b with sufficient pressure to withstand the normal pressure in the branch Y, but weak enough to yield to the abnormal pressure induced by the stoppage of the plunger. When the 100 piston a yields the piston rod c moves a lever d which at its opposite end carries a roller e which strikes a tappet f fastened on the tube Q and shifts the tube Q backward to the position which causes a return of the 105 plunger. In order to make sure of a sufficient movement of the parts the lever d is provided with a spring g which, as soon as the lever is forced past its dead center by the pneumatic piston, will carry it farther 110
- 120
- 125
- 130

and will complete the necessary length of stroke. Thus the termination of the forward stroke of the charging plunger is dependent upon the resistance which the plunger meets, and as the ore in the retort gradually fills the space from the rear end toward the mouth it is packed therein to a density determined by the setting of the pneumatic apparatus and the stroke of the plunger is gradually shortened. The succession of operations is automatic from the moment that the air pressure is turned into the mechanism.

We prefer also to stop the operation of the charging plunger automatically when a certain quantity of ore has been introduced into the retort. Mechanism for doing this is diagrammatically indicated in Fig. 8. It is controlled by a certain quantity of air which escapes from the cylinder Z at each operation of the latter. The cylinder Z has a small port *f'* in its side leading to a pipe *h* having two branches *j* and *k*. The pipe *j* passes through a lug *l* fixed on one side of a part *m* connected with the charging plunger and reciprocating therewith. Pipe *j* has an opening *n* therein which is covered when the lug *l* is at the rear end of its stroke and is uncovered as soon as this lug advances. It is at the forward end of the stroke of the charging plunger that a pressure of air passes through the pipe *Y* and displaces the piston *a*. At each such displacement therefore, a quantity of air is forced into the pipe *h*. But it escapes through the branch *j* and opening *n*, the lug *l* being in its advanced position. As the charging proceeds the stroke becomes progressively shorter. When the charging has proceeded to the desired limit the stroke will be so short that the lug *l* will not advance far enough to uncover the hole *n*, but will stand over this hole as indicated. This position will coincide with the admission of pressure through the pipe *Y* to the cylinder Z and the pipe *h*, being the position at the end of the forward stroke. When this condition arrives a pressure of air will be forced through the branch pipe *k* which will be used to cut off the valve which controls the supply of air to the apparatus.

A cam shaft *o* is used to control the supply of air, the cam *p* being in the full line position when the air valve is open, and being in the dotted line position when the air valve is closed. The cam shaft has an arm *q* which is pulled in the direction to close the valve by a spring *r*. When the valve is open however, the arm *q* is caught by a spring latch *s* mounted on a shaft *t* having an arm *u* in line with a rod *v* mounted to slide in suitable bearings and, when shifted to the rear, to move the arm *u* sufficiently to release the cam shaft and allow it to spring to the closing position. The rod

v is shown in its normal position to which it is moved by the arm *u*. The part *m* which reciprocates with the charging plunger has a lug *w* in line with the rod *v* but which in its rearmost position, shown in dotted lines, just strikes the end of the rod *v* without moving the latter. When the valve is to be closed a block *x* is thrust into the path of the lug *w* and is forced against the rod *v* to shift the latter to the rear and release the cam shaft which controls the valve. The block *x* is suspended by a flexible strip *y* from a diaphragm *z* in an air chamber 2 which communicates by a pipe 3 with the pipe *k*. A check valve 4 interposed between the pipes *v* and 3 allows the air to flow toward the latter freely but not to return except slowly through a small vent.

Now, when the charge is completed and the advance of the charging plunger has become so short that at the end of the stroke the opening in the branch *j* is covered and an air pressure is accumulated in the pipe *h*, such pressure will be exerted against the diaphragm *z* to throw down the block *x* so that on the short backward stroke of the plunger the lug *w* will press the block *x* against the end of the rod *v* and cause the closing of the air supply valve.

Each of the charging cylinders D is filled through an opening F from a screw conveyer 5 extending longitudinally of the furnace. These longitudinal screw conveyers are supplied from transverse screw conveyers 6 which have their rear ends offset, Figs. 100 1 and 3, and filled from chutes 7 which in turn receive their supply of ore from chain and bucket elevators 8. Only the uppermost chute 7 and its elevator 8 are shown, in order to avoid confusion. But it will be understood from Fig. 3 that the several chutes 7 are offset from each other transversely so as to register with the rear ends of the conveyers 6, and that the elevators 8 for the several chutes are offset in corresponding planes. The lower ends of the elevators 8 take their supply from a pocket in the forward end of the common bin 9. In order to keep the charging cylinders filled an excess of ore is continually supplied to the conveyers 5 and this excess passes out of the discharge ends of the conveyers 5 and downward through a vertical tube 10 to a horizontal screw conveyer 11 (Fig. 1) which conveys the material as indicated by the arrows to the pocket 12 of the bin constituting the lower end of the boot for the elevators 8.

The bin 9 (Figs. 1 and 3^a) is equipped with means for dragging or shifting the ore therein toward the end in which the elevators are located, so as to keep the latter constantly supplied and to maintain a substantially uniform level of ore in the bin. To keep a uniform level of ore in the pocket 12

of the bin a steady or constant supply is delivered to the elevator 8, thereby putting a uniform load on the driving mechanism for the elevator, and preventing undue strains or shocks that would be attendant, in the event the ore was irregularly or unevenly fed to said elevator. Chains 13 provided with sweeps 14 are driven in the direction indicated by means of sprockets 15 and 16 mounted on shafts carried in bearings on the lower ends of rack bars 17 which are raised and lowered by means of pinions 18 on overhead shafts 19. The shaft 20 carrying the forward sprockets 15 is driven through beveled gearing from the forward end of a shaft 21 of telescopic construction and pivotally mounted at its rear end above the rear end of the bin, where it is driven by suitable beveled gearing. As the rack bars 17 are lifted or lowered, and the sweeper chain with them, the driving shaft 21 will swing upward and downward about its pivoted rear end. When the bin 9 is, say one half full, the sweeper chain will be allowed to rest on the top of the ore and will operate to maintain the latter level. As the quantity of ore in the bin is reduced the sweeper chain will be lowered and the same conditions maintained with a full supply to the elevators until the bin is practically empty. This mechanism may be operated continuously or intermittently as desired by means of the usual clutches.

The shafts are driven at their rear ends from beveled gears 19^a (Fig. 2) on a cross shaft 22 which is driven by a belt 23 (Figs. 1 and 3^a) from a shaft 24 driven by any suitable means. The shaft 22 is geared by pinions 22^a and 22^b to the supplementary shaft 25 which drives the inclined shaft 21 through beveled gears 21^a and 21^b. The cross shaft 22 is provided with counter-weights 23^a suspended by chains or cables passing around drums on the shaft so as to balance the weight of the sweep-chain and connected parts which are to be lifted and lowered. The clutches and other details of this mechanism are not illustrated in full since they may be of any usual or suitable type.

The entire apparatus comprising the bin, conveyors and charging mechanism is mounted on a truck framed of longitudinal girders 24 (Figs. 1 and 3) connected at suitable intervals by transverse girders 25 and mounted on wheels 26 driven by electric or other suitable motors and traveling on rails 27 running parallel with the front of the furnace. The truck carries rails 28 extending transversely to the front of the furnace and the main frame of the machine is mounted on wheels 29 adapted to travel on these rails a short distance toward and away from the furnace so as to clear ob-

structions on the furnace while shifting longitudinally and, after shifting, to bring the charging apparatus into close engagement with the retorts.

Any suitable mechanism may be used for this clearing shift, such for example as that shown in Fig. 6, which represents one of a number of cylinders that constitute a shiftable connection between the main frame and the truck. The cylinder 30 is double acting so as to shift the carriage in both directions. Compressed air tanks 31 are supplied through a piston valve, the cylinder 32 of which communicates with the charging pipes 33 for the air tanks 31 and has an inlet pipe 34 from the source of compressed air, and vents 35 at opposite ends. When the piston 36 of the valve is at one end of its stroke it supplies air to one of the tanks 31, and relieves the pressure in the other; and when the piston is moved to the opposite end it reverses the supply and relief connections of the air tanks. The tanks 31 carry a quantity of oil and are connected at their lower ends through a valve 37 by which the height of oil in the two tanks can be equalized before operating the machine, and a supplementary valve 38 between their upper ends for the same operation. The oil is forced by the compressed air from the tanks 31 through needle valves 39 which adjust the speed of the mechanism, into the respective ends of the cylinder 30. When the control valve piston 36 is shifted to the position shown, the air pressure is admitted to the left hand tank 31 and relieved from the right hand tank, and oil is forced into the left hand end of cylinder 30, driving the piston 40 thereof to the right and shifting the piston rod 41 and the frame carrying bins, conveyors and chargers in one direction toward or from the furnace to the limit required. The shifting of the truck is then accomplished, or the charging of the retorts, after which the valve 36 is shifted to the opposite position and the frame carrying the bins, conveyors and chargers is moved in the opposite direction to permit the next movement or operation of the machine.

When the truck is shifted along the longitudinal rails it is important to stop it and hold it with the charging apparatus in direct line with the retorts. A suitable device for this purpose is indicated diagrammatically in Fig. 7. It is mounted on the truck and passes longitudinally over a tapered stop 42 mounted on the bed on which the truck travels. A cylinder 43 mounted on the truck communicates with a compressed air pipe 44 through a hand valve 45 and carries a piston 46 normally held up by a spring 47 and having a piston rod 48, which carries on its lower end a socket block 49, the socket of which fits the tapered stop 42. Guides 50

extend from the lower end of the cylinder, the block 49 having grooves embracing the guides 50. When the truck has been shifted laterally to approximately the desired position, the operator opens the valve 45. The block 49 is pressed down gradually on the tapered stop 42 and locks the block in position at the same time that it shifts it a little in one direction or another if necessary by reason of the tapered engagement of the block with the stop.

In charging retorts it is common for the operator to make a passageway in the upper part of the charge for escape of gases. This is referred to as "spieeing." Such a vent may be made by hand by thrusting a long pointed rod into the upper part of the charge. Or we may provide a mechanical device for doing the same thing. Such venting devices may be mounted alongside the charging devices at such a distance therefrom as to register with a charged column of retorts when the said devices register with a new column of retorts, and may then operate at the same time that the charging devices for the next column are operating. Or the venting devices may be mounted directly on the charging devices and be operated immediately after the charge is completed before the machine is moved to the next column of retorts. Each device consists of an air cylinder 51 (Fig. 9), the piston 52 of which is connected with a "spieeing" rod 53. The opposite ends of the cylinder are connected to an air supply tube 54 having an admission valve 55. Three way air cocks 56 at opposite ends of the pipe 54 are connected together by a link 57 so as to move in unison and so that when one is opened the other is vented. Thus by shifting the link 57 in one direction the rod will be advanced. Then by shifting it in the other direction the rod will be withdrawn. And the valve 55 may be closed when the device is idle.

Though we have described with great particularity of detail a certain specific embodiment of our invention, yet it is not to be understood therefrom that the invention is restricted to the particular embodiment disclosed. Various modifications may be made in detail and in the arrangement of the parts without departing from the invention as defined in the following claims. And while we have assumed that electric motors shall be used for moving the machine from place to place and for driving all the parts for supplying ore to the elevators and to the charging cylinders and that compressed air is used for the charging apparatus and the shift toward and from the retorts and for the locating and spieeing device, and have indicated these parts diagrammatically in order to make the operation of the apparatus

clearer, yet it will be understood that these subsidiary mechanisms may be operated by any suitable motive power and may be of various other designs than those illustrated.

What we claim is:

1. A machine of the class described including in combination a charging cylinder, means for supply material to said cylinder and a charging plunger operating within the cylinder to push the material therefrom into the retort and means for automatically retracting and advancing said plunger repeatedly and shortening the stroke thereof as the quantity of ore charged into the retort increases.

2. A machine of the class described including in combination a charging cylinder, means for supplying material to said cylinder and a charging plunger operating within the cylinder to push the material therefrom into the retort and means controlled by density of the charge introduced into the retort for limiting the succeeding strokes of the plunger.

3. A machine of the class described including in combination a feeding device and means controlled by the density of the material already fed into the retort for controlling the further operation of said feeding device.

4. A machine of the class described including in combination a charging cylinder means for supplying material to said cylinder and a charging plunger operating within the cylinder to push the material therefrom into the retort and means for automatically stopping the operation of the plunger when the retort has been filled to the desired extent.

5. A machine of the class described including in combination a feeding device for charging material into a retort and means controlled by the quantity already charged for stopping further operation of said feeding device.

6. A machine of the class described including in combination a charging plunger for feeding material into a retort, said plunger equipped at its end with a portion which occupies a greater area transversely of the retort on its forward stroke, then on its backward stroke and means operated by the plunger for varying the effective area of the end portion.

7. A machine of the class described including in combination a charging plunger for feeding material into a retort, said plunger equipped with a hinged disk adapted to swing to an extended position on a forward stroke and to a contracted position on a rearward stroke and means operated by the plunger for swinging said disk.

8. A machine of the class described including in combination a charging plunger

for feeding material into a retort, said plunger comprising an outer shell and an inner shell with a limited relative movement, and an end member which is expanded and contracted by such movement, so that the end member can be contracted on a rearward stroke to avoid dragging out material introduced on the forward stroke.

9. A machine of the class described including in combination a column of charging cylinders, conveyers communicating with the several cylinders to maintain a supply of material therein, means for feeding material from the several cylinders simultaneously into a column of retorts and means controlled by the quantity already fed into the retorts to stop a further feeding operation.

10. A machine of the class described in-

cluding in combination charging devices, a bin, means for transferring material from the bin to said charging devices and means for maintaining a substantially uniform level of material in the pocket of the bin in order to facilitate such transfer, said leveling means comprising chain sweeps adapted to be operated at different levels in the bin.

11. A machine of the class described including in combination devices for charging a substantially horizontal retort with ore, and means connected with said charging devices for making a longitudinal passageway in the upper part of the charge.

In witness whereof we have hereunto signed our names.

GEORGE W. WHIPPLE.
CLOISE H. BALDWIN.
